KANSAS.

DEEP-WELL-DRILLING APPARATUS AND THE LIKE.

Application filed November 5, 1925. Serial No. 67,007.

This invention relates to deep well drilling tools and more particularly to tools in which some part subject to rapid wear is to be held in a more lasting member, such as a drill bit body, for instance.

It is an object of the present invention to provide an automatic locking of the parts together in operating position, and at the same time readily disassemble the parts when desired, by manual manipulation.

Other objects will be manifest in the following specification of an embodiment of the invention illustrated in the accompanying drawings in which is shown a sectional view through the center line of a bearing and cutter held in a body member.

In the preferred embodiment, the invention consists of a body member (1) having a recess, the walls of which have a seat receiving formed ends of a bearing member (2) carrying a rolling cutter (3). The member (2) has a bore to receive a spring (4) which actuates a plug (5) and holds the plug as a lock between the body and bearing member. Shoulders formed in the body (1) carry the loads where the ends of bearing member (2) are fitted. The recess in body (1) receiving the end of plug (5) is of smaller diameter than the main portion of plug (5), which is, therefore, prevented from falling out. A hole (6) thru the outside of the body permits the insertion of a punch to compress the spring when cutter (3) and bearing (2) are to be removed. As all parts operate in mud slush the plug (5) is perforated (7) to permit drainage of any thin mud that accumulates about the plug (5), spring (4) or in the recesses in bearing (2).

In assembling, the body (1) will be formed to receive the member (2), the contacting surfaces being arranged to take all operating thrusts and loads. The invention automatically locks the parts in position when placed together. All parts are internally contained, and protected from abrasive action in operation in the well. The perforation of plug (5) reduces the area of its end exposed to fluid or other pressures through the hole in body (1) and thus prevents accidental unlocking and separation of the members in the well.

It will, of course, be understood that while the preferred embodiment illustrates the invention, applied to a rotary roller drill, the invention is not intended to be limited thereto, other applications of the invention may be readily made in well tools, where it is desired to lock in position some member normally working within another, as for instance, any member fitting into a recess and supported by the sides or walls thereof.

It will be observed that the rotary cutter 3, with its bearing member 2 and with the locking means 5 are all assembled previous to their insertion into the recess or pocket in the bit head 1 and they are introduced into said pocket or recess as one body. The locking means is self acting. Thus when the previously assembled parts are inserted into the pocket to such a point where the spring plug 5 aligns with the recess in the inner side of the pocket, designed to receive it, said plug will automatically spring into place and hold the assembled roller cutter organization against falling out. The duty that this locking plug performs is to prevent the said organization from falling out of place. It does not have to sustain upward thrust as this is borne by the shoulders on the walls of the pocket against which parts of the journal or bearing 1 contact.

Equalization of pressure of the fluid in the well will take place as between the inner face of the locking plug and the clearance space around the bit head because the fluid at the bottom of the well is free to enter through the bore in the plug into the recess in which the plug is located and this added to the force of the spring, will maintain the locking plug in position to hold the parts together.

Having thus described my invention, I claim:

1. In combination in a deep well drilling apparatus, a bit head having a pocket to receive a roller cutter organization, said or-

- ganization comprising a roller cutter, and a bearing assembled therewith to be inserted into or removed from said pocket as one body, and locking means carried by the bearing to be inserted with said bearing into the pocket as one body, said locking means engaging a part of the wall of the pocket to hold the organization therein.
2. In combination in a deep well drilling apparatus, a bit head having a pocket to receive a roller cutter organization, said organization comprising a roller cutter and a bearing assembled therewith to be inserted into or removed from said pocket as one body, and locking means carried by the bearing to be inserted with said bearing into the pocket as one body, said locking means engaging a part of the wall of the pocket to hold the organization therein, said pocket having a shoulder on its wall to be engaged by the bearing to sustain the thrust, substantially as described.
3. In combination in a deep well drilling apparatus, a bit head having a pocket, a roller cutter, and a bearing therefor, assembled to be handled as one body for insertion into or removal from said pocket, and means carried by the bearing for automatically interlocking with the wall of the pocket, substantially as described.
4. In combination in a deep well drilling apparatus, a bit head having a pocket, a roller cutter and bearing, a locking plug, and a spring for pressing said plug outwardly, said plug and spring being assembled with the bearing to be inserted into the pocket therewith as one body, said pocket having a portion to be engaged by the plug for holding the bearing in place, substantially as described.
5. In combination in a deep well drilling apparatus, a bit head having a pocket, a roller cutter together with a bearing member, and an automatic locking means assembled to be handled as one body for insertion into or removal from the pocket, said pocket having a portion to be engaged by said locking means for holding the bearing with its rotary cutter in place, said bit head having an opening affording access to the said locking means from without, for its release, said opening providing for drainage from said locking means, substantially as described.
6. In combination in a deep well drilling apparatus, a bit head having a pocket, a roller cutter organization fitted to said pocket and having automatic resilient locking means, said pocket having a recess in its wall to receive said locking means, and an opening through the wall to said recess by which access may be had from the outside for the release of the said locking means, substantially as described.
7. In combination in rotary roller cutter
- drilling tools, a bit head having a pocket, a roller cutter, a bearing therefor, having a recess in one end, a locking plug in the recess, and a spring for pressing said plug outwardly, said parts being assembled to be handled as one body for insertion into or removal from the pockets, said plug being perforated to communicate with the recess for drainage, said bit head having a recess to receive the plug, and an opening leading from said recess to the outside for drainage and for allowing access to be had to the plug for its release, substantially as described.
8. In a deep well drilling apparatus and in combination, a bit head having a pocket, a roller cutter organization, insertible into or removable from said pocket as one body, and locking means carried by the roller cutter organization as one body, wholly located between the walls of the pocket and automatically engaging a portion of one of said walls to hold the said organization in place, said locking means being removable only through the open mouth of said pocket, together with said roller cutter organization, said pocket having an opening in its wall for the manipulation of the lock, substantially as described.
9. In combination, a bit head having a pocket or recess, a roller cutter organization having a bearing member, and a roller cutter mounted thereon, which bearing member has a recess in its end, a locking plug and spring in said recess, the wall of said pocket having a portion to be engaged by the plug for holding the roller organization in place, and having also an opening leading to the outside of less diameter than the plug to expose a portion of said plug for its manipulation, substantially as described.
10. In combination in a deep well drilling apparatus, a bit head having a pocket, a roller cutter organization comprising a bearing, and a roller cutter mounted thereon, locking means carried by the bearing, and engaging the interior wall of the pocket, said bearing with the roller cutter and locking means being assembled to be handled as one body, and a passage through the wall of the pocket and past the locking means for the equalization of pressure of the fluid in the well on opposite sides of said locking means, substantially as described.
11. In combination in a deep well drilling apparatus, a bit head having a pocket, a roller cutter organization, having a locking device mounted thereon to be inserted into or removed from said pocket as one body with the organization, said locking device holding the said cutter organization within the pocket by automatically engaging the inner side of the wall of the pocket, said pocket having an opening through its

wall whereby access is had to the locking device for its release, substantially as described.

12. In combination in a deep well drilling apparatus, a bit head having a pocket, a roller cutter organization in said pocket, and locking means carried by the roller

organization as one body, and automatically engaging the inner side of the wall of the pocket, substantially as described. 10

In testimony whereof, I affix my signature.

FRED K. BLAUVELT.
